UNITED STATES PATENT OFFICE.

ALONZO J. GRIFFIN, OF WILKES-BARRÉ, PENNSYLVANIA.

DESIGN FOR A WIRE SCREEN.

SPECIFICATION forming part of Design No. 18,954, dated March 12, 1889.

Application filed January 22, 1889. Serial No. 297,201. Term of patent 3½ years.

To all whom it may concern:

Be it known that I, ALONZO J. GRIFFIN, a citizen of the United States, residing at Wilkes-Barré, in the county of Luzerne and State of Pennsylvania, have invented a new and useful Improvement in a Wire Screen, of which the following is a specification.

My invention relates to a design for a wire screen, which is more fully described herein-after in connection with the accompanying drawing, wherein the figure represents a plan view of a screen embodying my design.

Referring by letter to the drawing, A designates the frame, which is provided with the transverse parallel wires B B, and C C designate double loops, which intersect the said parallel wires and are connected, respectively, together by the connecting-strands D D. These double loops consist each of two single loops, E E, extending in opposite directions, the inner or intermediate wire, e, forming the inner sides of both loops E E. This intermediate wire, e, passes on one side of the wire B, and the wires e' e', which form the outer sides of the said loops, are extended respectively upward and downward to form the strands D D. Thus the loops, being arranged

on the parallel wires B B, are arranged in parallel series, and the corresponding loops of adjacent series, above and below, are connected by the said strands. The corresponding loops of the various parallel series are arranged on parallel lines perpendicular to the said series, and therefore the strands D, which connect the downwardly-extending loops of one series with the upwardly-extending loops of the adjacent series, are necessarily inclined to the parallel series and parallel with each other.

Having described my invention, I claim—
The design for a wire screen, consisting of double loops arranged in parallel series and comprising the oppositely-extending single loops E E and the parallel strands e', connecting the said loops, substantially as herein shown and described.

In testimony that I claim the foregoing as my own I have hereto affixed my signature in presence of two witnesses.

ALONZO J. GRIFFIN.
